Primary Examiner — Llorellys Martinez(74) *Attorney, Agent, or Firm* — Andrew F. Young, Esq.;
Lackenbach Siegel, LLP(57) **CLAIM**

The ornamental design for an emblem jewelry structure, as shown and described.

DESCRIPTION

FIG. 1 is a front top perspective view of my present invention.

FIG. 2 is a front bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dash-dash lines in the drawings represent portions of the emblem jewelry structure that form no part of the claimed design. The dash-dot-dash lines represent a claim boundary and form no part of the claimed design.
